UNITED STATES PATENT OFFICE.

ALBERT A. GABRIEL, OF PORTLAND, OREGON.

FURNACE.

Application filed November 8, 1921. Serial No. 513,655.

To all whom it may concern:

Be it known that I, ALBERT A. GABRIEL, a citizen of the United States, residing at Portland, county of Multnomah, State of Oregon, have invented certain new and useful Improvements in Furnaces, of which the following is a specification.

My invention relates to furnaces in general, and to hot air furnaces in particular, 10 the object being to provide the most complete combustion of the fuel and the employment of the greatest possible heat units in the products of combustion.

I accomplish the above object by means of 15 the construction illustrated in the accompanying drawing, which is a part of this application for Letters Patent, like characters of reference indicating like parts throughout the several views thereof, and 20 in which:

Fig. 1 is a perspective view of a furnace embodying my invention, parts being broken away to illustrate the construction: Fig. 2 is a sectional plan view upon the line 2—2 25 of Fig. 1: Fig. 3 is a sectional elevation upon the line 3—3 of Fig. 1: Fig. 4 is a sectional elevation of the fuel door and draft device thereon: Fig. 5 is a plan view of the grate.

The outer casing 6 of my furnace is of 30 oblong form with substantially semicircular ends, the fire box and combustion chamber being mounted substantially in the center of said casing. The fire box is composed of upper and lower horizontally disposed 35 plates 7 and 8 respectively, each plate having an oblong orifice therein. Surrounding said orifice in the upper plate 7 is a dome structure 9, closed at the upper end thereof, and within the orifice in the lower plate 8 40 is disposed a grate of novel construction.

At each end of the oblong orifice in said lower plate 8 is a semicircular dished grate member 10, said members being joined by side members 11, the upper edges of each 45 of said dished members and side members being rolled to form a ledge adapted to contact with the edge of the orifice in the lower plate 8 and thus support said grate members. Centrally disposed relative to said 50 side members 11 are two solid grate bars 12, each supported at its ends by the adjacent dished members 10, and intermediate each of said solid bars and the adjacent side member 11 is an open or barred grate member 13 also supported at the ends thereof 55 upon the adjacent dished members 10.

That portion of each of the plates 7 and 8 lying outside the dome 9 and grate members 10 and 11 are connected by pipes or tubes 14, and outside said tubes the plates 7 and 8 are connected by a vertically disposed plate 15 completely surrounding said tubes. A space is left between said plate 15 and the casing 6 entirely surrounding the fire box except at the front end thereof, at which point the plate 15 and casing 6 are brought into contact one with the other, as shown in Figs. 1 and 2.

Beneath the grate is the usual ash receptacle 15 with the ash door 16 thereon. 70

Closing the upper end of the casing 6 are two plate members 17 and 18 joined together by a tongue and groove construction 19, the forwardly disposed member 18 having thereon the hot air pipe 20 wherefrom hot air 75 is delivered from the furnace.

A stack, 21 is introduced into the fire box adjacent its lower plate 8, and a pipe 22 also connects the stack with the dome 9, there being a damper 23 in said pipe. 80

The fuel door of the fire box is of novel construction adapted to coact with the above described novel form of grate to provide complete combustion. Said door is composed of an outer member 25 completely closing the door aperture in the fire box, and having thereon an air duct entering adjacent the top of the door and extending downward thereon to open adjacent the bottom of the door, as shown at 26, the opening of said 90 duct into the atmosphere being closed by a door 27. Upon the inner member 28 of said door inclosing the duct 26 is secured a plate 29, there being a small space 30 intervening between said plate 29 and said member 28. 95

When the fire is lighted in the furnace, that portion of the fuel above the barred grate members 13 will burn rapidly because of the draft coming up through the grate members 13, while that portion of the fuel upon the solid grate members 12 will burn very slowly, gases being liberated from said latter fuel portion by means of the heat generated by the rapidly burning fuel portion. As the gases liberated from the centrally 105 disposed portion of fuel rise oxygen for their combustion is furnished by the draft of air entering the duct 26. The plate 29 becomes highly heated, and as the air enters the fire box from duct 26 it impinges upon the lower 110 end of said plate, and is thereby heated, the result being that a portion of said air is di-

rected upward through the space 30, and emerging from the top thereof is directed upon the products of combustion within the top of the fire box, thereby providing oxygen therefor and resultant complete combustion.

The greater portion of the products of combustion ascend into the dome 9 imparting a large portion of their heat thereto, and being thereby cooled they descend along the walls of said dome back into the fire box and thence outward between the tubes 14 into the space between said tubes and the fire box plate 15, imparting more of their heat to the tubes 14 when passing therebetween and to the plate 15 as they impinge thereupon. By the time the cooling products of combustion have descended sufficiently to reach the stack 21 they have parted with the major portion of their heat to the dome, tubes and fire box plate.

The air to be heated enters the furnace casing 6 at 31 and passes upward to the delivery pipe 20, some by way of the space between said casing 6 and the plate 15, and some through the tubes 14, being thus highly heated upon reaching the pipe 20.

The pipe 22 and damper 23 are used when starting the fire to provide a direct passage for the products of combustion before the furnace is thoroughly heated.

By this construction I obtain three essential features: First very large heating surface due to the plate 15, tubes 14 and dome 9; second very complete combustion due to the novel construction of the grate and fire box door; Third effective exhaustion of the heat units within the products of combustion by having the stack remove the same from substantially the level of the fire box floor.

My device may be made of any size, and constructed of any materials deemed con-

venient and suitable for a device of this character, and while I have illustrated and described a form of construction and arrangement of parts found desirable in materializing my invention, I wish to include in this application all mechanical equivalents and substitutes that may fairly be considered to come within the scope and purview of my invention as defined in the appended claim.

Having disclosed my invention so that others may be enabled to construct and to use the same, what I claim as new, and desire to secure by Letters Patent is:

In a furnace fire box: horizontally disposed plates connected by a vertical peripherally disposed plate; a plurality of air tubes connecting said horizontal plates adjacent said vertical plate; a single dome rising from the upper of said vertical plates within the space occupied by said tubes said dome being closed at the top thereof; dished grate members supported by the lower of said horizontal plates; solid grate members centrally disposed upon said dished members; barred grate members disposed upon each side of said solid grate members; a stack leading from said fire box substantially at the level of the lower of said horizontal plates; and a door having two vertically disposed air ducts therein the outer of said ducts communicating with the atmosphere outside the fire box.

In witness whereof I claim the foregoing as my own I hereunto affix my signature in the presence of two witnesses at Portland, county of Multnomah, State of Oregon, this 5th day of Oct., 1921.

ALBERT A. GABRIEL.
